UNITED STATES PATENT OFFICE.

JOHN F. CARPMILL AND HORACE G. HANCOCK, OF NEW BRITAIN, CONNECTICUT, AS-
SIGNORS TO NORTH & JUDD MANUFACTURING COMPANY, OF NEW BRITAIN, CON-
NECTICUT.

SNAP.

Application filed March 22, 1927. Serial No. 177,846.

This invention relates to improvements in snaps and has particular reference to such as may be employed for connecting a lead or leash with a dog collar or harness,—one object of the invention being to provide simple and efficient means to prevent displacement of the spring which operates normally to close the jaws of the device.

A further object is to provide simple and efficient means to lock the relatively movable members of a snap of the type to which the invention relates.

With these and other objects in view, the invention consists in certain novel features of construction and combinations of parts as hereinafter set forth and pointed out in the claims.

In the accompanying drawings,—

Figure 1 is a view illustrating an embodiment of our invention.

Figure 2 is a longitudinal sectional view with the device closed and locked.

Figure 3 is a similar view showing the device unlocked and open, and

Figure 4 is a detail view.

The snap comprises two levers 1 and 2 pivotally connected together at 3 and formed at their forward ends to provide jaws 4 which, when closed form an overlapping joint 5.

At their upper or rear ends, the levers 1—2 are provided respectively with arms 6—7, the arm 7 being provided with an elongated slot 8 through which the arm 6 passes and the latter is provided at its free end with a cross-head 9. A spring 10 is so cooperable with the levers 1—2 as to maintain the jaws of the device normally closed.

A cross-bar 11 extends across the slot 8 near one end thereof and a tongue 12 on one end of the spring 10 engages over this cross-bar in a manner to prevent longitudinal movement of the spring in one direction while longitudinal movement in the reverse direction is prevented by the engagement of shoulders 13 on said spring with the lever 2. The free end of the spring 10 engages in a groove 14 in the inner face of the lever 1 and the sides wall of this groove will prevent lateral displacement of the spring.

The lever arms 6—7 are so interconnected that when the snap is closed, a crotch 15 will be formed and in this crotch, a locking device 16 is adapted to engage in a manner to prevent the snap from being opened. 55 This locking device may conveniently consist of sheet metal (preferably resilient) bent upon itself to form two members 17—18 which are provided with openings 19 for the accommodation of the respective lever arms 6—7 and one of the members of the lock is provided with a laterally projecting lug 20 which overlies the cross-head 9 on the arm 6 when the device is in locked position, as shown in Figure 2. The members of the lock device are provided near their upper ends with holes for the accommodation of an eye 21 and with the shank of this eye, a loop or ring 22 is swiveled and adapted to receive the lead or leash. It will be understood that when in use, the jaws 4 will be caused to engage a suitable ring or loop on the collar or harness for a dog.

Having fully described our invention what we claim as new and desire to secure by Letters-Patent, is:

1. A device of the character described comprising two levers pivotally connected together and formed with jaws at their forward ends, a slotted arm projecting from one of said levers, an arm projecting from the other lever and passing through said slotted arm and provided with a cross-head, and a lock device through which said arms pass and adapted to engage between the free ends of said arms, said lock device having a laterally projecting lug to engage one of said arms.

2. A device of the character described comprising pivotally connected levers provided at one end with jaws, one of said levers provided at its other end with a slotted arm and the other lever provided with an arm passing through said slotted arm and having a head at its free end, and a lock device comprising two members having openings through which said arms pass and having a lug to engage one of said arms.

3. A device of the character described comprising two levers pivotally connected

together and each having a jaw at one end, one of said levers having a groove in its inner face, the other of said levers having an opening, a cross-bar extending across said opening, and a spring disposed between the levers and having a tongue at one end engaging over said cross-bar, the opposite end

of said spring engaging the opposite lever in the groove thereof.

In testimony whereof, we have signed this 10 specification.

JOHN F. CARPMILL.
HORACE G. HANCOCK.
